ATTORNEY.

UNITED STATES PATENT OFFICE.

RAY ELLIS PALMEE, OF ELMIRA, NEW YORK.

ROAD-RESURFACING APPARATUS.

Application filed December 6, 1927. Serial No. 238,145.

This invention relates to road re-surfacing apparatus, and has more particular reference to simple and efficient means for facilitating re-surfacing of water-bound bituminous and concrete roads to predetermined grades by the use of road re-surfacing drags of the type shown in my co-pending application upon road re-surfacing apparatus, Serial No. 220,984, filed September 21, 1927.

More particularly, the present invention aims to provide simple and efficient means which may be readily placed into practical use with the expenditure of a minimum amount of time and labor as well as at a relatively low cost, to furnish a track or way over which the runners of a road re-surfacing drag may be readily drawn and by means of which the drag may be caused to travel in the proper position and at the required elevation to insure resurfacing of the road at a predetermined grade.

Other objects will appear as the nature of the invention is better understood, and the same consists in the novel form, combination and arrangement of parts hereinafter more fully described, shown in the accompanying drawings and claimed.

In the drawings, wherein like reference characters indicate corresponding parts throughout the several views,

Figure 1 is a top plan view, partly broken away, showing a road re-surfacing drag operatively associated with means forming a track way constructed in accordance with the present invention;

Figure 2 is a side elevational view looking upwardly of Figure 1;

Figure 3 is a side elevational view, partly broken away looking downwardly of Figure 1;

Figure 4 is an enlarged transverse section taken on line 4—4 of Figure 1;

Figure 5 is an enlarged fragmentary vertical section taken on line 5—5 of Figure 2;

Figure 6 is a view similar to Figure 5 taken on line 6—6 of Figure 3;

Figure 7 is a top plan view of one of the track way forming disks, employed in connection with the runner of the road re-surfacing drag which is the innermost or inwardly of the edge of the road when the drag is employed for resurfacing the latter; and

Figure 8 is a top plan view of one of the disks employed in connection with the runner at the other side of the drag during the road re-surfacing operation.

Referring more in detail to the drawings, the form of road re-surfacing drag with which the present invention is employed embodies a pair of spaced parallel side rails or runners 5 rigidly connected as by means of transverse bars 6 and crossed braces 7, and having a blade 11 obliquely mounted therein for spreading the re-surfacing material in a smooth layer over the surface of the roadway, as clearly described in my above mentioned co-pending application.

In using a road re-surfacing drag of the type specified above, a plurality of steel pins or stakes 12 are driven into the ground along the edge of the roadway being surfaced so as to effectively guide the drag in a straight or proper path of travel when drawn ahead, the stake 12 being provided at suitable intervals to insure engagement of the outer side of the outermost runner 5 with a plurality of the stakes at all times.

In accordance with the present invention it is contemplated that the grade will be rock or laid out in any preferred or well known manner with the elevation at the outer edge of the roadway marked on the stakes 12.

I provide a number of relatively large disks 13 in a number of sets of different thicknesses, the disks of each set being of uniform thickness throughout and having central openings 13^a to permit the same to be readily placed over and onto the stakes 12. The disks 13 are of such diameter as to provide ample tracking surface at the inner sides of the stakes 12 for riding of the adjacent outer runner 5 of the drag thereover, and by providing one or more disks of selected thickness upon each of the stakes 12, the exposed upper disk surface at each stake may be provided level or flush with the grade mark on said stakes. As the normal elevation of the road surface being repaired will vary at different points, the disks employed in connection with each stake will be selected to effect the desired result as illustrated in Figure 3 wherein a single thick and a single thin disk are employed in conjunction with the first stake from the left of Figure 3, a

single thick disk is employed with the intermediate stake of said figure, and a thick disk together with two thin disks are employed in conjunction with the right hand stake of said Figure 3. The exposed upper disk surfaces related to all of the stakes will thus be provided in a common plane so that the outer side of the drag will be properly supported at the proper elevation in being drawn ahead over the disk. It will be noted that the disks are free to turn on the stake 12 and in this way facilitate the forward travel of the drag.

In addition to the stake 12 and disk 13 for guiding and supporting the outer side of the drag, I provide a plurality of relatively smaller disks 14 that are adapted to be placed and secured upon the surface of the roadway in position to have the inner runner 5 of the drag travel thereover. These disks 14 will also be provided in sets of different thicknesses so that they may be provided in proper thickness and number at different points along the center of the road to present upper surfaces flush with the predetermined grade whereby the inner side of the drag will be properly supported at the correct elevation during the forward travel of the drag in the re-surfacing operation. The disks 14 will be provided at suitable intervals so as to insure engagement of the inner runner 5 of the drag with a plurality thereof at all times, and in order to facilitate fastening of the disks 14 in their proper places upon the road, said disks are provided with central openings 15 which are enlarged or counter-sunk as at 16 at the upper sides of the disks to receive the heads 17 of spikes 18 which are driven through the openings 15 into the ground. In this way the heads 17 of the spikes 18 may be positioned to not project above the upper surface of the disks 14 and interfere with the riding of the inner runner 5 of the drag over the upper surface of said disks 14 at the proper elevation. The disks 14 are also preferably rotatable on the spikes 18 so as to facilitate the travel of the inner runner 5 of the drag thereover in case a greater amount of friction may be experienced between the runners and the disks at either side of the axes of the spikes 18. As shown in Figure 2, disks 14 will necessarily be provided of different thicknesses at different points, and in some cases a plurality of the disks 14 will have to be superimposed to present an upper disks surface at the required elevation.

A trackway provided in accordance with the above may be readily laid with the expenditure of a minimum amount of time and labor and at a comparatively small cost. Moreover, a minimum amount of friction between the track forming members and the runners of the drag will be had so as to facilitate travel of the drag with the ex-

pense of a minimum amount of power. With the grades properly run or determined, the disks may be properly laid by unskilled labor and the selection of disks of proper thickness or combined thicknesses will not consume an objectionable amount of time.

It will thus be seen that simple means is provided for insuring the production of a smooth and uniform surface for the road at given grades when the road re-surfacing apparatus is drawn over the disks or the trackway formed thereby.

What I claim as new is:—

1. Trackway equipment for road re-surfacing drags comprising a plurality of disks 80 of different thicknesses, and means to secure selected ones of said disks on the surface of the road singly or in superimposed relation at predetermined intervals and in parallel lines.

2. In a means for forming a trackway for supporting the runners of a road re-surfacing drag at predetermined grade elevations when drawn over the road to be re-surfaced, a plurality of stakes adapted to be driven at intervals along the edge of the road to guide the drag, and a plurality of centrally apertured disks of different thicknesses removably positionable upon said stakes to rest upon the road.

3. In a means for forming a trackway for supporting the runners of a road re-surfacing drag at predetermined grade elevations when drawn over the road to be re-surfaced, a plurality of stakes adapted to be driven at intervals along the edge of the road to guide the drag, and a plurality of centrally apertured disks of different thicknesses removably positionable upon said stakes to rest upon the road, said disks being rotatable on said stakes.

4. Trackway construction for runner-provided road re-surfacing drags, consisting in securing disks upon the road surface at intervals and in parallel lines, longitudinally of the road coincident with the path of the drag runners, with the disks of proper thickness at the respective intervals to support the drag at a predetermined grade elevation when drawn over said disks.

5. In a means for forming a trackway for supporting the runners of a road re-surfacing drag at predetermined grade elevations when drawn over the road to be re-surfaced, a plurality of stakes adapted to be driven at intervals along the edge of the road to guide the drag, a plurality of centrally apertured disks of different thicknesses removably positionable upon said stakes to rest upon the road, further centrally apertured smaller disks of different thicknesses having their apertures enlarged at the upper sides thereof, and spikes for securing the latter disks at intervals on the road parallel with said stakes, said spikes having heads

positionable in the enlarged portions of the apertures of the latter disks to lie below the upper surfaces of the latter.

6. Trackway equipment for road re-surfacing drags comprising a plurality of disks of different thicknesses, means to secure selected ones of said disks on the surface of the road singly or in superimposed relation at predetermined intervals and in parallel lines, said securing means permitting rotation of the disks.

7. Trackway equipment for road re-surfacing drags comprising a plurality of disks of different thicknesses, and means to secure selected ones of said disks on the surface of the road singly or in superimposed relation at predetermined intervals and in parallel lines, said disks being centrally apertured and provided in sets of different diameters, said securing means embodying grade mark-

ing stakes adapted to be driven at the edge of the road and to receive the disks of larger diameter.

8. Trackway equipment for road re-surfacing drags comprising a plurality of disks of different thicknesses, means to secure selected ones of said disks on the surface of the road singly or in superimposed relation at predetermined intervals, and in parallel lines, said disks being centrally apertured and provided in sets of different diameters, said securing means embodying grade marking stakes adapted to be driven at the edge of the road and to receive the disks of larger diameter, and spikes adapted to be driven through the smaller disks and having heads, said smaller disks having their apertures countersunk to receive said spike heads.

In testimony whereof I affix my signature.
RAY E. PALMER.
